UNITED STATES PATENT OFFICE.

JOHN M. KEMP, OF DES MOINES, IOWA.

MOLD FOR CEMENT CHIMNEY-SECTIONS.

1,285,217.

specification of Letters Patent. Patented Nov. 19, 1918.

Application filed December 15, 1913, Serial No. 807,349. Renewed March 29, 1918. Serial No. 225,534.

To all whom it may concern:

Be it known that I, JOHN M. KEMP, a citizen of the United States, and resident of Des Moines, in the county of Polk and State 5 of Iowa, have invented a certain new and useful Mold for Cement Chimney-Sections, of which the following is a specification.

The object of my invention is to provide a mold of simple, durable and inexpensive 10 construction, particularly designed for the manufacture of comparatively thin walled blocks, adapted for use in chimneys and the like.

More particularly, it is my object to provide a mold for the making of thin walled, 15 hollow blocks, said mold having inner and outer walls, which are readily removable, and being provided with new and improved means for locking the inner and outer walls 20 in proper position for making my blocks.

My invention consists in certain details, in the construction, combination and arrangement of the various parts of the device, whereby the objects contemplated are 25 attained, as hereinafter more fully set forth, pointed out in my claim and illustrated in the accompanying drawings, in which:

Figure 1 shows a vertical, transverse, sectional view through a mold, embodying my 30 invention, with plastic material therein.

Fig. 2 shows a top or plan view of the base with the pallet installed thereon.

Fig. 3 shows a horizontal, sectional view, taken on the line 3—3 of Fig. 1.

Fig. 4 shows a rear elevation of my improved mold with the top removed, and

Fig. 5 shows a horizontal, detail, sectional view of one of the devices for locking the outer walls in position.

In the accompanying drawings I have 40 used the reference numeral 10 to indicate generally the base or support of my improved mold. The base 10 has a smooth flat upper surface and is somewhat longer in 45 one dimension than the greatest distance between the outer mold walls. Adjacent to one end is secured an upright outer wall member 11, having a smooth inner face. The wall member 11 is provided at its lower 50 edge with an outwardly extending flange 12, which is secured to the base 10 by means of bolts 13. The wall 11 is also held in position by means of braces 14.

The pallet 15 is provided and is in the 55 form of a hollow square, one side of the pallet being adjacent to the wall 11, as shown

in Fig. 1. The pallet is provided in its upper surface, on each of its four sides with a groove 16, so that the lower edge of the cement block may be made with a concave 60 bead or ridge.

For purposes of convenience, I will call the wall 11 and the opposite outer wall the end walls and the other outer walls the side walls of my mold.

Arranged in a vertical plane, parallel with the vertical plane of the wall 11 and near the opposite end of the base 10 is the other end wall 17, which is secured to base 65 at its lower edge by means of hinges 18.

It will be understood that the pallet 15 fits snugly against the four outer walls. The side walls 19 are hinged at their lower edges to the base by hinges 18 and are provided on their inner surfaces, near their 70 ends, with vertical grooves 20, to receive the ends of the end walls 11 and 17. Portions 19^a of the walls 19 extend beyond the walls 11 and 17, as clearly shown in Fig. 3. For locking the four outer walls, I have provided the following means:

Near the middle of the outer surface of the walls 11 and 17, and near the upper portions thereof, are brackets 21, to which are pivoted oppositely extending rods 22. 85 The outer or free ends of the rods 22 are mounted in guide devices 23, secured to the rear surfaces of the walls 11 and 17, near their side edges, in such a manner as to permit certain pivotal movement of the rods 90 22 in a horizontal plane when the outer walls are in their vertical positions. The free ends of the rods 22 are bifurcated to receive the portions 19^a, as shown in Figs. 3, 4 and 5. Mounted between the extreme 95 bifurcated ends of the rods 22 are pivoted cams 24.

The portions 19^a are provided on their outer surfaces with grooves or notches 25. Formed preferably integral with the cams 100 24 are handles or levers 26. The parts just described are so arranged that when the four outer walls are assembled in their upright positions, the handles 26 may be turned to position adjacent to the side walls 19, when the thicker parts of the cams 24 will enter the grooves 25 and engage the portions 19^a as shown in Fig. 5, thereby firmly locking the four outer walls together. In the upper surfaces of the pallet 15, near 110 the inner edges thereof, are a plurality of notches or grooves 27. I provide four inner

- walls 29, each comprising two parts, divided on a vertical, central line, and secured together by means of hinges 30, so that said walls may fold inwardly at their centers. 5 Sufficient play in the parts of the hinges 30 is allowed to permit the inner walls to fold inwardly. The end walls 29 may be grooved and the side walls 29 tongued, as shown in Fig. 3. The walls 29 are provided at their lower edges with downwardly extending lugs 32, which, when the mold is 10 assembled, are received within the respective notches or grooves 27, as shown in Fig. 1.
- 15 Pivoted to one member of each wall 29 is a rod 33, and secured to the inner surface of the adjacent member of the adjacent wall 29 are parallel horizontally arranged eyelets 34. On the free end of the rod 33 is 20 an eyelet 35.
- 25 In assembling the inner walls 29, the side walls 29 are placed in position with the lugs 32 received in the grooves 27. The end walls 29 are then placed in position 30 slightly above their proper place, when installed with their centers folded inwardly somewhat. The centers are then moved outwardly on their hinges until the end walls 29 are in vertical position with the 35 tongues of the side walls 29 received in the grooves of the end walls 29 and with the members of each end wall in alinement. The end walls 29 are then slid downwardly until the lugs 32 thereof enter the slots 27.
- 40 The rods 33 are then swung around until the eyelet 35 is received between the eyelets 34 and a bolt 36 is dropped through the three eyelets. The inner walls are thereby locked firmly in position, as shown in Fig. 3.
- 45 Cement is then poured into the intervening space between the inner and outer walls to form a block having four walls. The cement may be tamped into position, as desired. Hinged to the wall 11 is a top or cover 37, comprising four portions similar in form to the pallet 15. Each of the portions of the top 37 is provided with a downwardly extending bead 38 for forming a groove in the upper edge of the block.
- 50 Suitably mounted on the wall 11 are stop devices 39, against which the cover 37 may rest when in its raised position.
- 55 After the space between the inner and outer walls has been filled with cement, or other plastic material 40, the mold may be taken apart in the following manner:
- 60 The bolts 36 are removed and the end members 29 are slid upwardly until the lugs 32 clear the pallet 15 and then said end members are folded inwardly along their middle lines and removed. The side inner walls 29 are then removed, the levers 26 are swung outwardly until the thin portion of the cam 24 is adjacent to the portion 19^a and the free ends of the rods 22 are swung

outwardly until the cams 24 clear the portions 19^a. The side members 19 may then be turned downwardly on their hinges. The end member 17 is folded downwardly, after which the block which has been formed may 70 be removed on the pallet and a new pallet placed in position, for the manufacture of another block. If desired, catch devices 40^a of the type used on window sashes may be employed for locking the walls 29 to the 75 pallet 15 to prevent upward movement of said walls 29 during the process of manufacture.

80 My improved mold has a number of advantages, many of which may readily be seen from the foregoing description. The parts are of comparatively simple and inexpensive construction. They may be quickly and easily assembled and when assembled are firmly held in position so that the plastic 85 material in the space between the inner and outer walls may be tamped thoroughly.

90 It is readily seen that the four outer walls are locked together and the four inner walls are locked together so that the concrete 95 blocks, when made, will be of uniform size and shape. It has been seen that the manufactured block will have on its lower edge a bead and in its upper edge a groove, which it will be understood, corresponds in size 95 with said bead so that when the blocks are placed in superposed position, the groove and bead will fit together. It will readily be seen that the chimney may be very readily built from blocks of this kind. After a 100 block has been completed in a mold, the walls of the mold are readily and easily taken away for removing the block and pallet. The parts may be quickly and easily repaired or replaced.

105 It will be noted that as shown in Fig. 3 the rods 33 in the assembled mold are connected with the inner walls at points located approximately midway between the vertical hinged line of said walls and the ends thereof, so that each end wall is firmly braced at the most appropriate point for holding it firmly against inward pressure from the weight of the concrete due to the tamping of the concrete.

110 It will be understood that many changes may be made in the details of the construction of my device without departing from its essential features, as set forth herein, and it is my intention to cover by this application any such changes which may be included within the following claim.

115 I claim as my invention:

120 A mold comprising a pallet, outer mold walls, four inner walls spaced from the 125 outer walls, said inner walls being each comprised of two sections hinged on a central vertical line to allow some play between the edges of the sections and being adapted to fold inwardly along said line, arms pivoted 130

to the inner surface of one section of each inner wall at a point substantially midway between the hinged line thereof and the end of said section, and means for locking said arms to the adjacent section of the next inner wall at a point substantially midway thereon between the hinged line of said section and the free edge thereof, said arms be-

ing so arranged that each inner wall is braced with relation to the two other inner walls thereby. 10

Des Moines, Iowa, October 31, 1913.
